DESIGN FOR A BOTTLE

Richard D. Kerckhoff, Richmond Heights, Mo.,
assignor to Pevely Dairy Company, St. Louis,
Mo., a corporation of Missouri

Application March 21, 1939, Serial No. 83,737

Term of patent 14 years

To all whom it may concern:

Be it known that I, Richard D. Kerckhoff, a citizen of the United States, residing at Richmond Heights, St. Louis County, State of Missouri, have invented a new, original, and ornamental Design for a Bottle, of which the following is a specification, reference being had to the accompanying drawing, forming part thereof:

Fig. 1 is a side elevation of a bottle showing my new design; and,

Fig. 2 is a vertical section of the bottle shown in Fig. 1.

What I claim is:

The ornamental design for a bottle, substantially as shown.

RICHARD D. KERCKHOFF.
